UNITED STATES PATENT OFFICE.

CLARENCE Q. PAYNE, OF NEW YORK, N. Y.

APPARATUS FOR GRADING FINELY-COMMINUTED MATERIALS.

1,354,063.

Specification of Letters Patent. Patented Sept. 28, 1920.

Application filed August 7, 1919. Serial No. 315,944.

To all whom it may concern:

Be it known that I, CLARENCE Q. PAYNE, a citizen of the United States, residing at New York, in the county of New York and

5 State of New York, have invented certain new and useful Improvements in Apparatus for Grading Finely-Comminuted Materials, of which the following is a specification.

This invention relates to apparatus for 10 the separation of finely divided or comminuted materials of various kinds into a series of groups of different sized particles without the use of screens.

In my copending application 277,724, I 15 have described an invention which embraces a novel method of and apparatus for grading quite finely divided material, which consists in acting upon it while it is conveyed lengthwise, upon an endless belt, preferably 20 transversely inclined, so that the material becomes stratified in transversely disposed grooves in the belt, with the coarser or granular particles on top, then discharging decreasing sized groups of granular particles 25 along the upper flight of the belt, while the finest particles are retained upon the belt by surface adhesion, aided by the static charge generated by its own air friction, until carried to the lower flight of the belt, 30 where they are removed.

One object of the present invention is to provide an improved apparatus based on the above method.

Another object is an apparatus for grading finely subdivided or comminuted materials, and capable of extending the sizing action in the direction of the finest sizes.

A still further object is to provide means for stratifying the particles while being 40 conveyed upon an endless belt, preparatory to sizing them.

Other objects will be apparent from the description.

For a fuller understanding of the invention, reference is had to the accompanying drawings, in which—

Figure 1 is a longitudinal section through an apparatus embodying the invention;

Fig. 2 is a section on the line 10—10, 50 Fig. 1;

Fig. 3 is a fragmentary sectional view on an enlarged scale of the belt. Fig. 4 is a longitudinal view of a special form of the invention in which longitudinal vibration 55 is imparted to the belt.

Figs. 5—9 illustrate different means for removing the finer particles from the lower flight of the belt by the application of various dispersive forces.

The invention is especially intended for 60 grading finely crushed materials, in the grading of which only a limited number of groups of granular particles is required. For this purpose I find that an endless belt operated at a high speed in such a position 65 that the transverse lines of the belt surface are horizontal, has certain advantages over an endless belt having its upper flight transversely inclined at a uniform or at a progressively varying angle. The belt may 70 also be operated in a longitudinally inclined position, although preferably with the transverse elements of the belt surface horizontal.

In Figs. 1 and 2 is shown a grading device 75 comprising an endless belt, 1 mounted upon pulleys 2 and 3 for travel in a substantially horizontal plane. The pulleys are supported in a suitable frame 4, and the casing 5 serves to completely inclose the endless belt. Between the end pulleys 2 and 3, the guide rollers 7—7 and 8—8 support the upper and lower flights respectively. A suitable belt tightener 6 serves to maintain 80 the proper tension upon the belt. The material to be graded is fed from a hopper 9 through a regulating gate 12 to the feed drum 13, and thence by guide plate 14 upon one end of the belt. By suitable operating mechanism the belt is driven at a high speed 85 in the direction indicated by the arrow.

While in the broader aspect of the invention the surface of the belt may be ungrooved, I preferably provide it with transverse grooves placed centrally and shorter 90 than the width of the belt, so as to leave an ungrooved portion 15—15 at each edge. This arrangement has the following purpose: When the belt 1 travels at a high speed, its grooved surface sets up air currents 100 which tend to disperse the particles sidewise as they are fed upon the belt. By leaving the edge portions 15 of the belt ungrooved, the effect of the air currents is here largely avoided. As a further means of 105 checking the disturbing effect of these air currents, I find it advisable to employ stationary protecting wings or shields 16—16, which are supported from the casing 5 and are held in close proximity to the ungrooved 110

edge portions 15 of the belt. In this way the fine particles are protected from lateral dispersion and other disturbing influences while undergoing sizing.

5 The grooves may also be placed in positions other than transverse. I prefer, however, the transverse position of the grooves, because they bring about the separation of the different sized granular particles after 10 stratification more expeditiously and more effectively than if the grooves were placed longitudinally or diagonally upon the belt surface. The progressively increasing inclination of the sliding surfaces of the 15 grooves 17-17 causes progressively increasing differences of statical moments and of frictional resistances among the different sized particles which are disposed in strata in the grooves. The resulting differences in 20 the resistance to motion of the different sized particles cause the successive strata to separate themselves from each other with least mechanical interference.

25 While the shape of the grooves may be widely varied, I find it convenient to so arrange their bounding faces that one of them forms an acute angle with the belt surface, while the other may form approximately a right angle therewith. The inclined faces 30 of the grooves, on reaching the discharge end of the belt, then form sliding planes or separating surfaces of increasingly steeper inclination along the curved surface of the pulley 3, as illustrated clearly in Fig. 3. 35 Here the coarsest particles are the first to detach themselves from the belt, and to be thrown off in definite directions, and in groups of decreasing sized particles, as shown diagrammatically in Fig. 3.

40 One particular advantage of this arrangement is the relatively small wear to which the surface of the belt is subjected. The distance which the coarse or granular particles move upon the belt surface while undergoing separation is merely that along the 45 sliding surfaces 17-17 of the grooves.

The different sized particles are collected in a series of separate chutes 18-18 at the discharge end of the belt. While I have indicated only three of such chutes, it is obvious that the sub-division may be carried 50 still farther. The size of the discharge pulley 3 may also be increased, or the curve through which the belt passes at its discharge end may be varied in different ways 55 so that the amount of the grading of the granular particles influenced by the separating forces exerted upon them may be increased as desired.

60 The high speed at which the belt is driven has a three fold purpose. It enables the stream of the material to immediately spread out in a thin layer as it comes in contact with the belt. It also aids in bringing about stratification of the material in

the grooves, and it tends to increase the static surface adhesion of the very finely comminuted particles to the surface of the belt. The static surface charge of the belt is generated partly by the friction of the 70 air against the surface of the belt when in motion and partly by the approach, pressure and recession of two electrically unlike substances, such as a rubber or leather belt, and an iron pulley when the former passes 75 rapidly around the latter. This charge is thus self-induced and causes the finer particles to be held to the belt by surface adhesion.

For certain kinds of material the high 80 speed of the belt, in connection with the slight sagging as it passes over the guide-rollers 7-7, Fig. 1, tends to set the particles in sufficient vertical vibration to bring about the desired stratification when the 85 feed-stream delivered upon the belt is sufficiently thin. The resulting freedom of movement of the particles among themselves thus causes the coarsest particles to appear on top, while the smaller particles falling 90 between their interstices, occupy succeeding lower levels until the finest particles of all rest in immediate contact with the surface of the belt along the bottoms of the grooves. This stratification is indicated diagrammatically in Fig. 3.

For still other varieties of materials, I have found that a more pronounced amount of vibration is desirable, and for such I prefer to apply the means illustrated in Fig. 4. 100 Here the end pulley bearings 20-20 may be supported by means of flexible hangers 21-21, and horizontal springs 22-22 support and adjust the proper tension of the belt 24. An eccentric weight 25 is rigidly 105 connected to the inner circumference of the pulley 26 at the feed end of the belt. The rotation of this weight as the pulley 26 revolves about its axis causes the tension of the belt to be rapidly and alternately increased 110 and diminished. The amount of the vibrating movement of the belt may be regulated to the required degree by varying the weight 25, and the compression of the springs 22-22. This vibration is transmitted to the 115 other end pulley 27 by means of the belt 24. The entire belt is thus set in rapid longitudinal vibration, while at the same time it is traveling about its end pulleys 26-27. In this way the particles fed upon the belt may 120 be given an increased amount of vibration in a longitudinal direction over that attained merely by the rapid motion of the belt itself, and are thus enabled to stratify themselves in the manner illustrated in Fig. 3, even 125 when fed in a comparatively thick feed-stream in the grooves of the belt.

It is important that no violent shocks or jars be applied to the pulley 27 at the discharge end of the belt, in order to avoid re- 130

5 removal of the finest particles held to the belt surface prematurely. For this reason I consider it advantageous to apply the vibrating effect upon the belt to the feed end by 10 means of a gradual and easy reciprocating motion, such as is obtained by the revolving eccentric weight 25, and also to diminish the amount of motion transmitted to the pulley 27 by the stretch of the belt intervening 15 between the two end pulleys. While I consider the means described above preferable for my purpose, yet other means may also be employed to bring about the longitudinal vibration of the belt in a manner 20 and for the purpose described. Such additional means I consider to be within the scope of my invention.

25 As explained in my co-pending application above referred to, the effect of surface adhesion is to cause the very fine particles 20 in contact with the belt to be retained upon it until they are removed from the lower flight of the belt by a greater force than that operating to retain them.

30 As the belt passes around the pulley 3, Fig. 1, the coarsest particles forming the upper layers of the stratified material are the first to be discharged. Then follow successively smaller or finer particles, until all 35 those which respond to differences of statical moments and of frictional resistances, aided by centrifugal force, have been discharged. Those still finer dustlike particles which resist the force of gravity and of centrifugal force, and are held upon the belt by 40 surface adhesion, are then carried over the curved surface of the pulley 3, and occupy inverted positions when they reach the lower flight of the belt.

45 The high speed of the belt, while increasing the force of attraction which is exerted upon the very fine particles, also increases the surface exposed per unit of time to the particles subjected to the force of adhesion. The grooving of the belt surface still further increases the effective surface of attraction.

50 A special advantage of my present invention consists in the extreme sub-division which can be effected among the very fine particles which are retained upon the belt by surface adhesion. When conveyed to the lower flight, these fine particles may then be removed by various means, for example, by 55 the use of cam-shaped rollers 28 and 29 to vibrate the belt, as shown in Figs. 1 and 4, by means of air jets, shown in Figs. 5 and 6, by means of a series of grounded metal points to dissipate the static belt charge 60 shown in Figs. 7 and 8, or by induction from a wire carrying a high tension alternating current placed close to the belt surface shown in Fig. 9. Any of the above devices may be applied in more than one position, and may also be varied in their effects

in applying them. For the purpose of illustration I have shown at 28-29, Fig. 1, cam-shaped rollers which cause the belt to vibrate vertically at two places along its lower flight. By placing the cam-rollers in different relation to the belt, so as to vary the amount of the vibration at different parts of the belt, the group of fine particles removed by the rollers 28 may be somewhat coarser than the extremely fine particles removed by 70 the cam roller 29, collected by the screw conveyor 30, and discharged at 31, while the finest of the end products is collected and removed at 32. By thus detaching the more easily removed particles, and therefore the 80 coarser among them first, it is possible to segregate in this way groups of extremely minute particles more perfectly than has heretofore been possible by mechanical means. 85

I claim:

1. Apparatus for the sizing of finely comminuted material, comprising an endless belt and means for operating the belt to cause the finer particles to adhere to the 90 surface thereof, means for varying the resistance to the motion of the different-sized granular particles along the discharge end of the belt, means for collecting separate groups of said granular particles and 95 means for removing the finer particles adhering to the belt, from the lower flight thereof.

2. Apparatus for the sizing of finely comminuted material, comprising an endless 100 belt and means for operating the belt to cause the finer particles to adhere to the surface thereof, means for varying the direction of discharge of the different sized granular particles of said material from the 105 curved end of the belt by varying their statical moments and frictional resistances thereon, means for collecting separate groups of diminishing sized particles and means for removing the finer particles 110 adhering to the belt from the lower flight thereof.

3. Apparatus for the sizing of finely comminuted material, comprising an endless belt having horizontal transverse grooves 115 and means for operating the belt to cause the finer particles to adhere to the surface thereof, said grooves being shaped to gradually vary the resistance to the motion of the granular particles of said material along 120 the discharge end of the belt, means for collecting separate groups of granular particles and means for removing the finer particles adhering to the belt from the lower flight thereof. 125

4. Apparatus for the sizing of finely comminuted material, comprising an endless belt having horizontal transverse grooves, means for operating the belt to cause the finer particles to adhere to the surface of 130

the belt, means for imparting longitudinal impulses to one end support of the belt, means for collecting separate groups of diminishing sized granular particles discharged from the end of the belt and means for removing the finer particles adhering to the belt, from the lower flight thereof.

- 5 5. Apparatus for the sizing of finely comminuted material, comprising an endless belt having horizontal transverse grooves and means for operating the belt to cause the finer particles to adhere to the surface thereof, said grooves being shaped to gradually vary the resistance to the motion of 10 the granular particles of said material along the discharge end of the belt, means for imparting longitudinal impulses to one end support of the belt, the said grooves being shaped to gradually vary the resistance to 15 the motion of the granular particles of said material along the discharge end of the belt, means for collecting separate groups of granular particles and means for removing the finer particles adhering to the belt 20 from the lower flight thereof.

- 25 6. Apparatus for the sizing of finely comminuted material, comprising an endless belt having horizontal transverse grooves, means for operating the belt to cause the finer particles to adhere to the surface thereof, means for feeding the material upon one end of the belt, means for imparting longitudinal impulses to one end support of the belt to cause stratification of the material 30 in the grooves, said grooves being shaped to gradually vary the resistance to the motion of the granular particles of the material along the discharge end of the belt; means for collecting separate groups of said granular particles and means for removing the finer particles adhering to the belt from the lower flight thereof.

- 35 7. In apparatus for the sizing of finely comminuted material, an endless belt having transversely disposed grooves, each groove being defined by a wall substantially at a right angle to the belt surface and a surface which forms an acute angle with the belt surface, and means for operating the belt to cause the finer particles to adhere to the surface thereof.

- 40 8. In apparatus for the sizing of finely comminuted material, an endless belt having transversely disposed grooves, each groove being defined by a wall substantially at a right angle to the belt surface and a surface which forms an acute angle with the belt surface, means for imparting impulses to one end support of the belt, means for operating the belt to cause the finer particles to adhere to the surface thereof and means for removing the finer particles adhering to the belt from the lower flight thereof.

- 45 9. In apparatus for the sizing of finely comminuted material, an endless belt having

transversely disposed grooves along its central portion, and whose edge portions are ungrooved in combination with air current protecting shields supported above the ungrooved edge portions of said belt.

70

10. In apparatus for the sizing of finely comminuted material, an endless belt having transversely disposed grooves along its central portion and whose edge portions are ungrooved, each groove being defined by two faces, one approximately perpendicular and the other inclined to the belt surface and wind protecting shields supported above the ungrooved portions.

75

11. An apparatus for the sizing of finely comminuted materials composed of various sized particles, comprising an endless belt, the transverse lines of whose surface are horizontal, means for rapidly moving the belt, means for charging the material upon one end of the belt, means acting upon the lower flight of the belt to separately discharge groups of different sized particles therefrom and means for separately receiving said groups.

80

12. An apparatus for the sizing of finely comminuted materials composed of various sized particles, comprising an endless belt the transverse lines of whose surface are horizontal, means for charging the material upon one end of the belt, means for stratifying the material upon the belt, means for separately receiving groups of different sized particles discharged from the curved surface at the end of the belt, means acting upon the lower flight of the belt to separately discharge groups of different sized particles therefrom and means for separately receiving said groups.

85

13. In apparatus for the sizing of finely comminuted material, an endless belt, means for rapidly moving the belt and means acting on different parts of the lower flight of the belt and in different degrees to separately remove different sized particles therefrom.

90

14. In the method of separating finely comminuted material according to size which consists in charging the material upon an endless belt, rapidly moving the belt to cause the very fine particles to adhere to the surface of the belt and removing them from the lower flight thereof, the step which consists in acting differently on different parts of the lower flight of the belt to separately remove different sized particles therefrom.

95

15. An endless belt, means for rapidly moving the belt and means operating upon the lower flight of the belt for vibrating different portions thereof in different degrees.

100

16. An apparatus for sizing finely comminuted materials composed of various sized particles comprising an endless belt having

105

transversely disposed horizontal grooves, means for rapidly moving said belt, means for feeding the material upon one end of said belt, means for longitudinally vibrating the belt to cause stratification of the particles with relation to their sizes within said grooves, means for separately receiving

groups of diminishing sized particles along the curved surface of the belt at its discharge end, and means for removing from 10 the lower flight thereof a plurality of finer sizes adhering thereto.

In testimony whereof I affix my signature.
CLARENCE Q. PAYNE.
